BUTTON SEWING MACHINE

Morehead Patterson, New York, and James J. McGinley, Williston Park, N. Y., assignors to American Machine & Foundry Company, a corporation of New Jersey

Application March 26, 1951, Serial No. 217,645

45 Claims. (Cl. 112—110)

This invention relates to sewing machines, and more particularly to improvements in sewing machines which sew buttons and like fastening devices to materials, such as men's and women's coats and the like. The machine constituting this invention is adapted to attach buttons to the work in such manner that there is provided a thread "shank" or "post" by means of which each button is supported thereby away from the work.

According to the present invention, buttons are sewed to the desired material with a relatively short thread passing through the eye of a needle which is projected back and forth by opposed needle bars through the material and selected button holes in such a manner that the thread travels in closed continuous paths. In this manner one or more or any desired number of complete loops of thread are made to bind the button to the work. Mechanism is also provided for winding several loops of thread about the post attaching the button to the work, and means are provided for locking the windings against unwinding in order to securely attach each button to the work.

The invention constitutes improvements to button sewing machines of the type disclosed in Johnson et al. Patent 2,451,495, and especially to improvements which make it possible to attach each button to the work in such a manner that no thread, or a minimum of thread, such for example a single stitch, appears on the under surface of the work or the material to which the button is secured. The invention therefore makes it possible to attach buttons to the work in a manner closely simulating "hand" sewing.

The present invention solves the problem of "blind" stitching or sewing a button to the material to which it is attached. If desired, all of the thread passing through the material may be obscured from view, although it may be preferred to have a portion of at least one loop of the attaching thread visible on the under side of the work. The desirable results of the invention are accomplished by folding the work, such as an article of clothing, and locating the folded edge in the path of travel of the needle which is passed back and forth through a button and the folded edge of the work. The plane of the button is located substantially at right angles to the path of travel of the needle, and the button and folded edge of the work are moved alternately, laterally and longitudinally at proper times during the sewing operations in order that the thread may be passed back and forth through selected holes in the button.

At the conclusion of the formation of a plurality of loops attaching the button to the work, the button is swung through 90°, such that the plane of the button lies in a plane parallel to the path of travel of the needle and the work is substantially at right angles relative to the path of the needle so as to locate or position the loops of thread connecting the button to the work in the path of travel of the needle. The button and work are then moved back and forth out of the needle path so that on one stroke, the needle passes on one side of the loops

2

and on its next stroke, it passes on the other side of the loops. This winds or wraps the loops connecting the button to the work and forms what is known in the trade as a "post" or "shank." After a suitable number of post forming wraps of thread has been made, the thread is anchored against unwrapping. This can be accomplished by moving the needle through the loops and windings forming the "shank" or through the work at any suitable point where the thread secures the button to the work, the former being preferred. The locking of the thread against unlocking completes the sewing operation.

It is an object of the invention to provide an improved sewing machine for attaching buttons and similar fastening devices to materials or work, such as articles of clothing and wearing apparel, and especially to wearing apparel in which it is desired to have such fastening devices secured thereto with a "shank" or "post" supporting the button or fastening device away from the surface of the garment to which it is attached.

It is a further object of the invention to provide a button sewing machine having means which insure against the breakage of needles, as the latter are moved back and forth through the material to which buttons are sewed.

It is the further object of the invention to provide improved means for supporting a button in different planes relative to the work to which it is being sewed in order that the button can be sewed and the "post" or "shank" which attaches it to the work can be wound or wrapped, the thread attaching the button secured against loosening, and wherein no thread, or a predetermined amount of thread appears on the surface of the work, thereby making it possible to sew buttons mechanically in a manner closely simulating the best type of hand sewing.

The invention also consists in the provision of mechanism for feeding buttons automatically from a source of supply, supporting them relative to the work at different positions during the attachment of each button to the work, and moving the work with respect to the needle as the latter moves back and forth through the work, and exteriorly thereof during the sewing operations.

The invention also includes the provisions of a novel work supporting table which is movable in a generally four-motion path of travel during the sewing and "post" winding operations, and also to a novel work supporting gauge plate mounted on the table and adapted to hold the folded edge of the work during the entire sequence of operations involved in attaching a button to the work.

It is an added object of the invention to provide improved mechanism for sewing buttons to desired materials including a moveable work and button supporting table having novel means of supporting the button and work relative to the needle which moves alternately through the work and selected button holes, and through selected button holes exteriorly of the work, and improved thread handling devices for properly manipulating the thread during the sewing and post-wrapping and locking operations.

A further object of the invention is the provision of a button sewing machine having means for feeding buttons from a source of supply to a button chuck which supports each button in a plurality of positions relative to the work during the sequential operations of attaching each button to the work in a manner closely simulating the best type of hand sewing.

With these and other objects not specifically mentioned in view, the invention consists in certain combinations and constructions which will be hereinafter fully described, and then specifically set forth in the claims hereunto appended.

In the accompanying drawings which form a part of this

specification, and in which like characters of reference indicate the same or like elements:

Fig. 1 is a side elevation of the button sewing machine with parts broken away to illustrate the general driving mechanism of the machine;

Fig. 1A is partial isometric view of the locking arrangement on the clutch control lever;

Fig. 2 is a side elevation of the machine on a slightly larger scale showing the upper needle bar control mechanism, the cam operated material supporting table and the button manipulating mechanism;

Figs. 3 and 3A when joined on line A—A illustrate a plan view of the synchronized driving means of the button manipulating and work handling mechanism of the machine;

Fig. 4 is an isometric view illustrating the button aligning, button gripping and button turning mechanisms;

Fig. 5 is a side elevation, partly in section of the button aligning head;

Fig. 6 is an isometric view of the upper looper actuating mechanism and the thread tensioning device connected therewith;

Fig. 7 is a plan view of a suitable cam for imparting the desired motion to the material supporting table;

Fig. 8 is a plan view of a suitable cam for providing the desired motion to the material or work supporting table.

Fig. 9 is a plan view of the material or work supporting table.

Fig. 10 is an end elevation of the same as seen from line 10—10 of Fig. 9;

Fig. 11 is a side elevation of the button gripping chuck;

Fig. 12 is an end elevation of the same as seen from line 12—12 of Fig. 11;

Fig. 13 is a rear view of the delivery end of the button chute;

Fig. 14 is an end elevation of the same as seen from line 14—14 of Fig. 13;

Figs. 15 to 21 and Fig. 23 are side views illustrating the successive steps of sewing a button to the material;

Fig. 22 is a plan view illustrating schematically a preferred form of stitching path during button sewing operation;

Fig. 24 is a detailed sectional side view illustrating the first step in post winding operation;

Fig. 25 is a plan view of Fig. 24;

Figs. 26 and 27 are end views illustrating two of the consecutive steps in the post winding operation;

Fig. 28 is a plan view illustrating the material and the attached button after completion of the button sewing and post winding operation;

Fig. 29 is a schematic side view illustrating a modified form of button sewing in which the first stitch is completely hidden in the material (blind stitch);

Fig. 30 is a view showing a modified method of post winding in a figure eight thread movement;

Figs. 31 and 32 show cams suitable for use in sewing and making the modified post winding shown in Fig. 30; and

Fig. 33 is a view showing a sharp end-blunt end needle which may be used for sewing buttons.

Referring to Figure 1, the button sewing machine which may be of the same general type as that shown in Johnson Patent 2,451,495, consists of a center support frame 30 and a combination end frame and housing 32, the frames being secured to and spaced by supporting members 34.

An upper needle bar 36 and a lower needle bar 38 arranged in opposed axial alignment are provided with actuating members 40 and 42, respectively. Actuating member 42 is connected to an arm 44 (Fig. 1) extending from the forward end of a lever 46 which at its rearward end is provided with an arm 48 carrying a cam roller 50 engaging a cam track 52 in cam 54. A rotatable hub

160 referred to more in detail hereinafter provides oscillating motion to lever 46 and arm 44, which in turn imparts vertical reciprocating motion to lower needle bar 38. Lever 46 is loosely mounted on a horizontal shaft 56 (Fig. 1) which is supported at each end by suitable bearing brackets 58 and 60 conveniently attached to the frame of the machine.

Actuating member 40 of upper needle bar 36 is connected to an arm 62 (Fig. 2) of lever 64 loosely mounted on a horizontal shaft 66. Arm 62 is provided with a lug 68 carrying a horizontal stud 70 which engages with the head of an adjustable screw 72 secured to and projecting vertically from the free end of an arm 74 extending from lever 76 also loosely mounted on horizontal shaft 15 66 supported by bearing bracket 80 (Fig. 1) and bearing lug 82 which projects from a bridge 84 (Figs. 1 and 2). The latter, and bracket 80, are suitably secured to frame 32. Arm 74 of lever 76 also carries a horizontal stud 86 which by means of tension spring 88, is connected to horizontal stud 70 projecting from lug 68 of lever 64, thus providing a permanent, but yieldable connection between levers 64 and 76. At its rear portion lever 76 is provided with an arm 90 (Fig. 1) mounting a cam follower 92 which engages cam track 52 of cam 54. In Fig. 1, since cam 54 is shown in section, cam follower 92 is shown out of engagement with track 52. Cam 52 provides oscillating motion to levers 76 and 64, the latter through arm 62 imparting vertical reciprocating motion to upper needle bar 36 which is operated in synchronism with lower needle bar 38.

Upper needle bar 36 is guided in suitable bushings, which may be similar to those shown in Johnson Patent 2,386,800. These bushings are carried by lug 94 projecting from the forward end of bridge 84 (Figs. 1 and 2). 25 Lower needle bar 38 is also guided in suitable bushings in lug 95 constructed and supported in the same general manner as disclosed in Johnson Patent 2,386,800, and further description thereof is deemed unnecessary. This mechanism employs a double pointed needle 96 having a point at each end and an eye located between its points or ends, preferably about midway of its length, through which the thread passes.

The machine also is equipped with a looper arm 98, the general principle of which is the same as that disclosed in Johnson Patent 2,386,800. However, since the button sewing action of this machine is divided into a button sewing operation and a post winding operation, it is desirable to have a slower looper section during the sewing operation and a fast looper action during post wrapping operation. To accomplish this task, looper arm 98 is mounted on a horizontal shaft 100 (Figs. 1 and 6). Between its ends, and preferably in its central portion shaft 100 carries a slidably clutch member 102 which is provided with a key 104 (Fig. 6) slidably engaging with a key way 106 in shaft 100. At its ends clutch member 102 (Figs. 1 and 6) is provided with one tooth clutch faces 108 and 110, respectively. The central portion of clutch member 102 is provided with a groove 112 which engages with a suitably bent rod 114 projecting from lug 116 adjustably secured to an oscillating shaft 118 which is actuated with a button manipulating chuck, as described hereinafter.

During button sewing operations, clutch member 102 is shifted to the left by rod 114, causing clutch face 108 65 of member 102 to engage with clutch jaw 120 which is an integral part of arm 122 loosely mounted on looper shaft 100. Arm 122 is connected by rod 124, to lever 126 pivotally mounted on a stud shaft 128 (Fig. 6) suitably secured in the frame of the machine. Lever 126 is formed with an arm 130 which at its free end carries cam roller 132 (Figs. 3 and 6) engaging with an open cam 134 loosely mounted on shaft 136. Cam 134 provides the desired oscillating motion to looper arm 98 during button sewing operation when clutch jaw 120 of oscillating arm 122 is in engagement with cam face 108.

of clutch member 102 connected to looper shaft 100 by means of key 104. Cam 134 is continuously rotated by means of sprocket 138 (Figs. 1 and 3), which in the embodiment illustrated herein, is integral with the hub of cam 134 loosely turning on shaft 136. Sprocket 138 is driven by chain 140 from sprocket 142 mounted on shaft 144. Secured to shaft 144 is a sprocket 146 which is driven by a chain 148 by sprocket 150 mounted on shaft 136. Shaft 136 carries a gear 152 which meshes with and is driven by gear 154 on shaft 156 (Fig. 3) 10 connected to a suitable gear train (not shown) in housing 32. This gear train is driven by a gear 158 (Fig. 1) which is an integral part of a hub 160 loosely mounted on a horizontal stationary stud shaft 162. The latter is provided with a flange 164 formed integrally therewith. Screws secure flange 164 to the vertical wall of housing 32 (Fig. 1). Needle bar actuating cam 54 also is secured to hub 160. As shown herein cam 54 forms an integral part of a V-belt pulley 168 which is driven by belt 170 from pulley 172 forming an integral part of member 174 of a conical clutch designated generally 173, the action and operation of which will be described hereinafter. Also secured to hub 160 is a looper operating cam 176 constructed and designed to impart to looper arm 98 a different and faster movement during post wrapping operations of the machine. Cam 176 (Figs. 1 and 6) is engaged by cam follower 178 pivoted to the free end of cam lever 180 loosely mounted on looper shaft 100. In the illustrated embodiment lever 180 forms an integral part of clutch jaw 182. The arrangement of parts is such that when clutch member 102 is shifted to the right, the one tooth clutch face 110 of member 102 engages with jaw 182 at which time the action of cam 176 upon cam lever 182, will be transmitted through jaw 182 and clutch member 102 to looper shaft 100 and hence to looper arm 98.

In order to prevent undue side motion of clutch jaws 120 and 182 when being engaged by clutch member 102, each jaw is provided with a slot 103 and 183, respectively (Fig. 6), which engage pins 105 and 185, respectively. These pins are secured to shaft 100 and protrude through 103 and 183, permitting their respective jaws free rocking, but no sideward movements. When clutch member 102 is in engagement with jaw 182, arm 122, oscillated by cam 134, will rock freely on shaft 100 without imparting any motion thereto. On the other hand, when clutch member 102 is in engagement with jaw 120 of arm 122, jaw 182 is disengaged, and arm 180, oscillated through cam 176, will rock freely on shaft 100 without imparting any motion to it.

Male clutch member 174 which drives the entire machine, and of which pulley 172 forms a part is loosely mounted on horizontal shaft 184 supported in a sleeve bearing of a hub 186 supported by and journaled in suitable ball bearings of a bearing bracket 188 secured to support plate 190 mounted on the main frame of the machine (Fig. 1). Integral with hub 186 is a pulley 192 which by means of a belt 194 is continuously driven from a suitable source of power (not shown), such as a motor. The face of pulley 192 is provided with a clutch drum 195 which, when engaged by male clutch member 174 drives the entire button sewing machine.

Attached to horizontal shaft 184 is a clutch collar 198 which engages with a clutch fork 200 fulcrumed on stud 202 projecting from the frame of the machine. Integral with the hub of clutch fork 200 is an arm 204 connected by a link 206 to one end of bell crank lever 208 pivoted to a stud 210 held by a suitable bracket 212 secured to the frame of the machine. The other end of bell crank lever 208 is pivotally connected to block 214 which slidably engages with the free end of a vertical rod 216. The other end of rod 216 is pivoted to an arm 218 formed on and projecting from control lever 220 pivotally supported to the frame of the machine. Rod 216 and block 214 are also resiliently connected through a compression 75 244.

spring 224 surrounding a portion of the free end of said rod and confined between a collar 226, secured to said rod, and the top surface of block 214. This construction provides a resilient means of throwing in clutch 173.

The upper end of control lever 220 is provided with an extension 228 which on its upper free end carries a horizontal pin 230 freely engaging with the rim or side edge of a shoulder 232 of sleeve member 234 slidably supported on the free end of horizontal shaft 162. One end of sleeve member 234 is provided with a flange 236 having secured thereto a one tooth male lock jaw 238 provided for the purpose of engaging with a complementary one tooth female lock disc 240 at the end of a cycle of the machine, so that the latter machine operations are always stopped at the end and started at the beginning of a cycle.

Lock disc 240 is secured to pulley 168 and hub 160 which, mentioned heretofore, is loosely mounted on horizontal shaft 162. A collar 242 attached to shaft 162 prevents any axial movement of hub 160 on shaft 162. When the machine is not in operation, lock jaw 238 is held in engagement with lock disc 240 by compression spring 244. This spring encircles the free end of shaft 162 and is confined between stationary plate 246 and hub 248 of sleeve member 234. Since upright plate 246 is rigidly mounted on the frame of the machine, spring 244 exerts its pressure against hub 248 and tends to maintain lock jaw 238 in engagement with lock disc 240 on pulley 168. Control arm 220 at its lower free end carries a pivotally mounted block 250 which slidably engages with the forked end of arm 252 attached to shaft 254 supported in a suitable bearing of bracket 212. Also secured to shaft 254 is a lever 256 which at its free end is connected by link 258 to armature 260 of solenoid 262 mounted on support bracket 264 attached to bracket 212. As shown, control arm 220 carries an outwardly projecting stud or pin 266. When the machine is stopped pin 266 butts against a vertical pin 268 (Fig. 1A) extending outwardly from a hub 270 loosely mounted on stud shaft 272 held by a lug of bracket 274 (Fig. 1) attached to the frame of the machine. The free end of arm 276 formed on hub 270 is provided with a slot in which engages a pin 278 carried by armature 280 of a solenoid 282 supported by bracket 284 secured to the frame of the machine. A tension spring 286 attached to arm 276 and anchored to the frame of the machine acts to urge pin 268 into contact with pin 266 of control arm 220. The operation of the clutch and driving control, as well as the cycle control just described, is as follows:

When the operator is ready to start the machine, he trips the suitably bent starting lever 288 (Fig. 1) which is conveniently supported by the bridge 84 of the sewing machine. The tripping of lever 288 causes the momentary closing of a switch 290 which closes a circuit including the coil of solenoid 262 thereby energizing solenoid 262, thereby causing downward movement of armature 260 and lever 256 on shaft 254. Arm 252 is moved thereby 60 in the direction indicated by the arrow shown in Fig. 1.

Since the upper end of arm 252 is connected to the lower end of control lever 220, the former causes the latter to move sideways, thereby effecting a disengagement of pin 266 from pin 268 on arm 276. When this occurs spring 286 pulls arm 276 upwardly and causes pin 268 to slide along pin 266, thus acting to lock arm 220 from returning to its original position. Since arm 220 is pivoted at 222, its upper free end 228 is moved also in a sideward direction, but opposite to that of the lower end. This movement causes pin 230 acting upon shoulder 232, to impart an axial movement of sleeve member 234 along shaft 162, which disengages jaw 238 from lock plate 240 on pulley 168. The same movement of sleeve member 234 also causes a compression of spring 75 244.

The swinging motion of control lever 220 effects a downward motion of arm 218 which through rod 216, collar 226 and spring 224 rocks crank lever 208. When bell crank lever 208 is rocked in this manner through link 206, arm 204 and clutch fork 200, clutch collar 198 on shaft 184 is moved in such a manner as to cause an engagement of the clutch member 174 with the constantly driven clutch drum 196, and thus, through pulley 172, belt 170 and pulley 168 effecting the drive of the entire sewing machine. To prevent sleeve member 234 and jaw 238 from turning, shoulder 232 of sleeve member 234 is provided with a lug 291 (Fig. 1). This lug is provided with a bore in which slides a horizontal stud 293 projecting from and held by a bracket 294 attached to the frame of the machine.

The stopping of the machine at the end of a cycle is effected by a control lug 296 mounted on a cam 298 (Figs. 2 and 3). During each machine cycle lug 296 passes a stationary switch 300 and closes it momentarily. The closing of switch 300 makes a circuit including the coil of solenoid 282 (Fig. 1) thereby energizing solenoid 282 momentarily, and causing its armature 280 and arm 276 to move downwardly thus effecting a disengagement of pin 268 with the side of pin 266 on lever 220. As soon as pin 268 moves out of engagement with pin 266, compression spring 244 pressing against hub 248 of sleeve member 234, urges the jaw 238 into engagement with lock plate 240, and further rotation of pulley 168 is stopped precisely at the end of the cycle. Since pin 268 is out of engagement with the side of pin 266, control lever 220 is moved backward at the same time to resume the position it occupied before the machine was started, whereupon pin 268 again comes to rest against the butt end of pin 266 of lever 220, as shown in Fig. 1A.

Switch 300 (Figs. 2 and 3) is mounted on bracket 302 attached to the frame of the machine and its actuating member preferably is provided with a roller 304. Cam 298 is mounted on shaft 306 protruding from gear reduction housing 308 (Figs. 1, 2 and 3). The reduction gears (not shown) in housing 308 are driven by shaft 310 protruding from housing 308, sprocket 312 secured thereon and chain 314 from sprocket 316 secured to shaft 136 mentioned heretofore.

The button sewing machine embodying the invention also is provided with a thread puller 318 (Fig. 1). Thread puller 318 is attached to the free end of arm 320 mounted on one end of horizontal shaft 322 rotatably supported in bracket 324 (Fig. 1) fastened to frame 30 of the machine. Secured to the other end of shaft 322 is an arm 326, carrying a roller 328 engaging in a track formed by a pair of spaced bars 330 mounted on gear 154. It will be evident that when gear 154 is rotated, shaft 322 driven by means of the connections described, rotates thread puller 318. Since the construction and operation of thread puller 318 is substantially the same as that shown and described in Johnson Patent 2,386,800, further showing and description thereof is deemed unnecessary.

In the embodiment selected for illustrating the invention, the material or work M to which a button or similar fastening means is to be sewed, is folded over the free end of a support member such as a gauge plate or tongue, designated generally 332 (Figs. 9 and 10) with the folded edge portion to which the button is to be sewed extending beyond the edge of plate 332 and properly gauged for sewing.

Since it may be desired to position the end of plate 332 nearer or farther from the path of travel of needle 96 in order to attach buttons to fabrics of different thicknesses, plate 332 is so formed that it can be adjusted as desired. A suitable manner of forming plate 332 is to make it of two main parts 335 and 337, adjustably secured together, as by a screw extending upwardly from plate 337 through an elongated slot 339 in plate part 335. A wing nut 341 is provided for securing the parts together in desired adjusted position.

Plate 332 is attached to pin 334 resting in a groove in round supporting bar 336 rigidly attached at its center portion to the upper portion of a vertical stud shaft 338 rotatably supported in boss 340 of work supporting table 5 342 (Fig. 10).

Pin 334 is rotatably held in the groove of supporting bar 336 by means of flat spring plate 344 attached to the upper portion of vertical stud shaft 338. The lower end portion of shaft 338 is clamped to a suitably shaped bearing lug 346, which carries a horizontal stud shaft 348. The forked end of a U- or V-shaped lock member 350 is pivoted on shaft 348. Projecting from the under side of lock member 350 is a lock stud 352 which when in locked position, engages with slot 354 in an arc-shaped 10 15 lock lug 356 secured to the lower side of work supporting table 342. One arm of lock member 350 is provided with a trip finger 358 the upper free end of which extends partially over the top side of the gauge plate 332.

In order to fold the cloth or material over gauge plate 20 332, the operator moves trip finger 358 in the direction of the arrow shown in Fig. 10 thereby disengaging lock stud 352 on lock member 350 from slot 354 of lock lug 356. Gauge plate 332 can then be moved sideways in the direction of the arrow shown in Fig. 9. After stud 352 is disengaged from slot 354 when the operator releases trip finger 358 the bottom of stud 352 rides on top surface 357 of arc-shaped lock lug 356 while plate 332 is moved sideways about its pivot 338. The operator can then lift the free end of plate 332 upward and fold the cloth or material M thereover in such a way that the point or mark on the material at which a button is to be sewed is located properly at the center point of the free end of plate 332, see Figs. 9 and 10. Plate 332 with material M held in place by the operator is then lowered into operative position relative to work supporting table 342, as shown in Fig. 10, and swung sideways towards the needle 96 until lock stud 352 drops into slot 354 thereby automatically locking plate 332 in sewing position. After a button is sewn to the work or material M, the operator again trips finger 358 to effect a disengagement of stud 352 from slot 354 in order that plate 332 can be moved, as described above, to position the work or material M for sewing the next button.

The machine is provided with a presser foot 360 adapted to be moved into and out of engagement with the work or material M to which buttons are to be sewed by means of a manually operated treadle, such as a knee actuated pedal 362 (Fig. 3A). When pedal 362 is depressed, presser foot 360 is raised above the 45 50 work on gauge plate 332, and the work can be shifted as desired, or plate 332 can be swung to and from operative position.

Presser foot 360 also functions as a needle guide and as means for preventing unwinding of the loops of thread 55 formed during a part of the sewing cycle in wrapping the "post" or "stem" of thread attaching the button to the work or material M. These functions will be described further hereinafter as the description proceeds. Knee pedal 362 forms part of a vertical lever attached 60 to horizontal shaft 364 (Fig. 3A) loosely supported by a pair of bearing lugs 366 mounted on one of the supporting members 34 of the machine frame. An arm 368 secured to shaft 364 is connected by link 370 (Figs. 1 and 3A) to one arm of a suitably shaped lever 372, 65 pivoted to stud 374 held by bracket 376 attached to the frame of the machine. The other arm lever 372 engages a fork formed by two vertically spaced lugs 378 and 380 (Figs. 2 and 3A) secured to vertical rod 382 slidably supported in lugs 384 and 386 projecting from the front 70 end of bridge 84.

In the illustrated embodiment lug 386 forms an integral part of presser foot and needle guide 360. The position of presser foot 360 with respect to plate 332 is controlled by a collar 386 (Fig. 2) adjustably mounted on the upper 75 end of rod 382. This rod is encircled by a tension

spring 388, the ends of which are confined between stationary lug 384 and a collar 390 on rod 382. In order to prevent the presser foot 360 from lifting except when the knee pedal 362 is depressed by an operator, an additional tension spring 392 (Fig. 3A) is provided. Spring 392 encircles a portion of horizontal shaft 364 and exerts tension in the proper direction by having one end attached to collar 394 on shaft 364. The other end of spring 392 is held by one of the stationary bearing lugs 366. Springs 388 and 392 insure that presser foot and needle guide 360 will always maintain the work or material M resiliently and firmly positioned on gauge plate 332, until pedal 362 is pressed to lift rod 382 and presser foot 360 upwardly, as described. In order that the work and a button to be attached thereto may be positioned properly, at all times during the sewing operations relative to the needle, work supporting table 342 on which gauge plate 332 is pivotally supported, is given a compound closed path of movement in a substantially horizontal plane. Table 342 in the embodiment selected for purposes of illustration is reciprocated sideways, and also back and forth in order to enable needle 96 to pass in a predetermined manner back and forth through the holes in a button B. In accordance with the preferred manner of operating table 342, the under side thereof is provided with three downwardly extending spaced supporting lugs 396. One lug is slidably supported on a stud shaft 398; the other lugs are slidably supported on stud shafts 400 (Figs. 3A and 9).

Each stud shaft 400 is secured to a pair of spaced arms 402 which extend upwardly from a sleeve or elongated hub 404 (Figs. 2, 3A and 10) loosely mounted on horizontal shaft 406. The ends of shaft 406 are mounted in suitable bearing brackets 408 attached to the upright flange of supporting members 34. Stud shaft 398 is secured to a pair of spaced arms 410 extending upwardly from a sleeve or elongated hub 412 loosely mounted on horizontal shaft 414. One end of shaft 414 is held by a bearing bracket 408; the other end thereof is secured to bridge bracket 416 (Fig. 3A) supported at one end by shaft 406 and at the other by tie rod 418 attached at both ends to bearing brackets 408. Hub 412 also is provided with a lug 420 (Figs. 2 and 3A). A pin 422 carried by lug 420 is pivotally connected to the forked end of a suitably shaped connecting member 424 which at its free end is provided with an adjustable screw 426 engaging one arm 428 of bell crank lever 429 (Fig. 3A); the other arm 430 of bell crank lever 429 carries a cam roller 432 maintained in constant engagement with cam 434. One end of spring 436 is attached to an arm 438 projecting from hub 404; its other end is anchored to tie rod 418.

Cam 434 is mounted on a vertical shaft 440 (Figs. 3 and 7). As cam 434 is rotated by shaft 440 oscillating back and forth motion or movement to the left and right, as viewed in Figs. 3 and 3A, is transmitted to work supporting table 342 through arm 430, arm 428, member 424, lug 420, hub 412 and arms 410. Bell crank lever 429 formed by arms 428 and 430 is pivotally mounted on an upright stud 442 (Figs. 2 and 3A) held in a suitable boss of bridge bracket 416.

Also secured to the top end of vertical shaft 440 is a cam 444 which is tracked by a cam follower 446 pivotally mounted on stud 448 carried by cam lever 450 loosely mounted on upright stud 442. The free end of cam lever 450 carries another roller 452 (Figs. 2 and 3A) which engages with the blunt end of a horizontal stud shaft 454 adjustably secured to a lug 456 mounted or formed on and projecting from the under side of work supporting table 342. A tension spring 458 is provided to assure constant contact of stud shaft 454 with roller 452, which through cam lever 450 also assures constant engagement of cam roller 446 with cam 444. One end of tension spring 458 on one end is hooked to stud 460 (Figs. 3A and 10) projecting from

table 342; its other end is anchored to pin 462 fixed to horizontal stud 464 attached to a vertical flange of one of the frame support members 34.

Cam shaft 440 is driven by means of worm gear 466 (Fig. 3) from a worm 468 mounted on horizontal shaft 470 supported by and protruding from a housing 472 which also supports cam shaft 440 and encloses worm gear 466 and worm 468. Housing 472 is suitably supported by and suspended from stationary shaft 406 and tie rod 418. Shaft 470 is driven by sprocket 474 attached thereto (Figs. 2 and 3) by chain 476 running on driving sprocket 478 secured to horizontal shaft 144 mentioned heretofore. Shaft 144 is supported by a suitable bearing bracket 480 attached to the rear wall of stationary thread guide drum 482 suitably secured to the frame of the machine. The loose end of thread T is disposed above drum 482 by thread puller 320 during the operation of the machine in the same general manner as disclosed in the above referred to Johnson patent.

Buttons B to be sewed to material M are either fed by hand or from an automatic hopper of suitable design into an inclined button guide chute 490, the top portion of which is loosely supported in a suitable slot of an angle iron bracket 492 attached to a vertical flange of a cover plate 494 (Fig. 3). Mounted on the rear wall of the lower portion of chute 490 is a stud 496 (Figs. 3A and 4) which loosely rests in an angular slot 498 of a bracket 500 attached to and suspended from lug 94 of bridge 84. Stud 496 is provided with a shoulder which normally rests against the front side of bracket 500. The free end of stud 496 which extends through slot 498 to the rear side of bracket 500, as viewed in Figs. 3A and 4, is provided with tension spring 502 and collar 504 to make the lower support or button chute 490 yieldable in a sideward direction.

Button chute 490 consists chiefly of a substantially rectangular channel 506 provided with suitable slots. Buttons B are inserted in the flared top end of channel 506 with their peripheries engaging the bottom of channel 506, thus permitting them to roll downwardly in chute 490 with the bottom side or face of each button facing the material and operator. The bottom or discharge end of chute 490 is positioned in front of a button aligner and ejector 510 (Figs. 3A and 4) and has a hole 508 (Fig. 13) provided in the rear wall of channel 506 to permit ejector 510 to move therethrough and push the lowermost button in channel 506 therefrom into a button chuck 520. The front wall of the bottom portion of chute 490 is formed with a suitable opening to permit this ejecting operation. The bottom or discharge end of channel 506 is provided with a stop lug 512 (Figs. 4 and 14) to prevent the buttons from dropping out of chute 490.

In order to prevent buttons B from falling out of the opening in the front wall of chute 490, as they arrive at the bottom of channel 506, the latter is provided with a pair of yieldable button retaining fingers 514 (Figs. 13 and 14), which at one end are loosely or pivotally attached to the rear wall of channel 506. The free ends of finger 514 are formed into U-shaped lugs 516 which project over the top and bottom edge of channel 506, respectively, and prevent the lowermost button in chute 490 from falling out of the opening in the front wall of the bottom portion of channel 506 during the aligning and before the ejecting operation.

It is essential in the automatic feeding of buttons incident to the operation of the machine constructed in accordance with the invention that every button be positioned relative to the work with its holes always located in exactly the same position above or on the material. The mechanism herein described insures this positioning of buttons and that the needle can pass properly through the button holes during the sewing operation, which, as a rule, follows a predetermined pattern.

Since buttons B in rolling down channel 506 may ar-

rive at the bottom or discharge end thereof with their holes in almost any unpredictable position, it is of utmost importance to align or reposition each button with its holes arranged to permit unobstructed passage of needle 96 therethrough before it is ejected from channel 506 and pushed into button chuck 520 which supports and holds it firmly during the entire sewing operation.

Buttons of different diameter can be handled and sewed to material. The spacing of holes in buttons is fairly uniform even though diameters vary. If a smaller or larger button than that shown in Fig. 4 is to be sewed to the work chuck 520 can be removed by loosening set screw 521, and a different block 598 and chuck 520 substituted. Chute 490 is also removed, and a new chute 490' designed to accommodate the selected button is clipped to the machine in place of the chute 490 removed.

A suitable mechanism for aligning holes in buttons arriving at the bottom end of the button chute 490 is shown in Figs. 3A, 4 and 5. This mechanism includes a horizontal plunger 522 (Figs. 3A, 4 and 5) rotatably and slidably supported by bearing block 524 (Figs. 2 and 3A) mounted on bracket 526 attached to the frame of the machine. The forward end of plunger 522 is provided with a head piece 528 (Fig. 5) preferably having a tapered edge secured thereto and slidably supporting a pair of horizontal pins 530. In the device illustrated two pins 530 are shown. If desired three or four pins could be used. Pins 530 are concentrically spaced in such a way as to correspond with the respective centers of a pair of opposed holes in a button. Each pin 530 is provided with an enlarged blunt end 532 held resiliently in contact with the rear side of head piece 528 by compression spring 534 confined in a bore 536 (Fig. 5) in plunger 522. The point of each pin 530 preferably is conical in shape in order to permit easy engagement with holes in buttons and enable the pins to operate effectively even when there may be a slight difference in distance between the centers of button holes from that of the pins 530.

The shank of plunger 522 is provided with longitudinal flutes or grooves 538 (Figs. 3A and 4) which mesh with gear 540 mounted on shaft 542 supported by bearing block 524. A cam lever 544 is also secured to shaft 542. A cam follower or pin 546 carried by lever 544 runs in cam track 548 of drum cam 550 mounted on shaft 552. Shaft 552 is driven by a sprocket 554 (Figs. 2 and 3) through chain 556 which is driven by sprocket 558 mounted on shaft 306. The rear portion of plunger 522 (Figs. 3A and 4) is provided with an annular groove or recess 560 in which runs a pin 562 held by and projecting from cam lever 564 loosely mounted on a stationary stud shaft 566 held by and projecting from bearing block 524. Cam lever 564 is also provided with a cam finger or lug 568 which contacts a cam 570 mounted on shaft 552 mentioned heretofore. A tension spring 572, wound around stud shaft 566 and having one end attached to the hub of cam lever 564 and its other end secured to a collar 574 (Fig. 3A) secured to stationary stud shaft 566, urges cam lug 568 into engagement with cam 570.

A button B resting at the bottom end of button chute 490 is aligned or repositioned during the running period of the machine, i. e. during the time the preceding button B is sewed onto the material. During this period, plunger 522 is advanced towards the face of button B by cam 570 and pin 562 on cam lever 564 engaging recess 560 in plunger 522 until headpiece 528 and pins 530 have contacted the face of the button. At this time, due to its yieldable mounting the bottom portion of button chute 490, is also pushed slightly forward. This movement, due to the action of spring 502 on chute support-stud 496, creates a tension on the face of the button against pins 530. Plunger 522, under the action of drum cam 550 upon cam lever 544 and gear 540, is then oscillated clockwise and counterclockwise, causing pins 530 to find and enter into one pair of opposed holes on the button. The tension exerted by spring 502 upon chute 490 and the button causes chute 490 to move slightly backwards again.

Ample time is provided to oscillate plunger 522 and for pins 530 to find and engage with the holes in the button before the repositioned button is ejected from chute 490. When oscillation of plunger 522 stops due to a dwell in cam 550 the holes in the next button to be ejected from chute 490 are located in the desired position for sewing operations in the next cycle of the machine.

With the cloth or material M properly disposed upon gauge plate 332, as described heretofore, the operator, 10 before starting the machine, presses knee pedal 576, which effects the ejection of the button from the bottom of chute 490 and its delivery into button chuck 520. Knee pedal 576 is secured to a suitably bent rod 578 (Figs. 3 and 4) loosely mounted in a suitable bearing lug 580 (Fig. 15) projecting from one of the brackets 408. Secured to rod 578 is an upright actuating finger 582 (Fig. 4). The free end of finger 582 engages an elongated cam slot 584 formed in horizontal plate 586 mounted on one end of lever 588 pivoted to a stud 590 (Figs. 3 and 4) fixed to frame member 30. The other end of lever 588 (Figs. 3 and 4) is positioned to engage dome shaped end 592 of ejector plunger 522. Hence a depression of knee pedal 576 through finger 582 and plate 586 rocks lever 588 and causes the free end thereof to engage dome shaped end 592 of the plunger 522 and move plunger 522 to the left, as viewed in Fig. 4. This forward movement of plunger 522 disengages button B from clamp lugs 516 which are yieldably connected by means of spring 594 (Figs. 13 and 14). A continued forward motion of plunger 522 brings 20 button B, carried by pins 530 into contact and finally in engagement with a button chuck, designated generally 520. In the embodiment selected for purposes of illustration see Figs. 4, 11 and 12, chuck 520 includes a pair of opposed clamping jaws 596 and 597. Jaw 596 is rigidly mounted on chuck holder 598; jaw 597 is pivotally mounted on stud 600 held by supporting plate 602 attached to chuck holder 598. Pivoted jaw 597 is yieldingly connected to rigidly mounted jaw 596 by spring 604.

In order to assure proper seating of a button pushed 40 by pusher 522 between jaws 596, 597 fixed jaw 596 is provided with suitable button guide lug 606. Chuck holder 598 is provided with a short shaft 608 which is rotatably supported in bracket 610 secured to the top face of work supporting table 342. In Figures 2, 3A and 4, the end of shaft 608 is shown provided with a slotted crank-like cam lug 612. If desired however, lug 612 could be made of a separate member suitably attached to shaft 608. A pin or cam follower 614 mounted on one arm of lever 616 engages slot 615 in lug 614. Lever 616 is pivotally mounted on a stud shaft 618 held in bracket 620 secured to the top face of the traveling work supporting table 342. Arm 622 of lever 616 is provided with a wiggle pin 624 (Fig. 2) connected to lever 626. The upper end of pin 624 is seated in conical seat 628 on lever 622; its lower end is seated in a conical seat 630 on lever 626, thus providing a flexible connection between lever 626 and arm 622.

Lever 626 is pivoted to stud shaft 632 held by bracket 634 attached to housing 32. A link 636 (Figs. 2 and 60 3A) connects lever 626 and arm 638 clamped to one end of shaft 118. A cam lever 642 fixed to the other end of shaft 118 carries a cam follower 644 (Figs. 2 and 3) which, during post winding operations, engages with, and during sewing operation is disengaged from cam 298.

As mentioned heretofore, shaft 118 also has secured thereto lug 116 which through rod 114 operates clutch member 102 which controls the action and speed of movement of looper arm 98 during sewing and post winding operations. A tension spring 646 encircling shaft 632 has one end attached to lever 626. Its other end is anchored to collar 648 fixed to (Fig. 3A) stationary stud shaft 632. Spring 646 functions to maintain follower 644 on cam lever 642 in contact with cam 298 and, when it leaves cam 298, urges it in such direction to cause downward motion to arm 638. This movement of arm 638

through link 636, also causes a downward movement of arm 622 through wiggle pin 624, held in flexible contact with lever 626 by means of tension spring 650.

Downward movement of arm 622 effects upward movement of arm 615, which through its connection with crank-like cam lug 612, causes the stud shaft 608 of chuck holder 593 to rotate approximately 90°, thus moving button clamping jaws 596 and 597 of button chuck 520 from a substantially vertical button receiving position, as shown in Figs. 3A and 4, to a substantially horizontal position. A stop screw 652 held by a suitable lug 654 (Figs. 2 and 3A), located beneath arm 638 is provided to arrest the latter when jaws 596 and 597 have reached their desired substantially horizontal position or the button sewing position in the illustrated embodiment of the invention.

The turning of jaws 596 and 597 of button chuck 520 results therefore in turning a button held in chuck 520 from receiving position to a face-up sewing position where the button B is located exactly over the spot on work or material M to which it is to be sewed. The machine is so timed, and cam 298 is so designed, that after the sewing operation, cam roller 644 again contacts cam 298 and thereby, through the connections mentioned above, effects a turning of button chuck 520 from the substantially horizontal sewing position back to its substantially vertical or "post winding" position, after which the post winding operation commences. It is evident that jaws 596 and 597 are located in a substantially vertical plane when a button is delivered theretofrom and when the "post" is being wound.

A pair of properly spaced stop pins 656 held by flange 658 (Figs. 3A and 4) on bracket 610, are provided to limit the movements of crank lug 612 and locate button chuck 520 in correct operative position for button sewing, and "post" winding, and button delivery or vertical position. Button chuck 520 is turned only twice during one cycle of the machine, i. e. from vertical to horizontal for the sewing operation and from horizontal back to vertical for the post winding operation. When the work with a button sewed thereto is removed from plate 332, the button is pulled edgewise manually from between jaws 596, 597. This leaves empty button chuck 520 positioned for delivery of the next button thereinto.

In order to provide sufficient clearance and avoid interference between upper needle bar 36 and of button chuck 520, when the latter is turned as described above, cam 298 is provided with two properly spaced and suitably shaped lugs 660, which during each revolution of cam 298 contact a suitably shaped cam follower 662 (Figs. 2 and 3) attached to the free end of cam lever 664 projecting from one end of an elongated hub or sleeve 666 loosely supported on shaft 118. The other end of sleeve 666 is provided with an arm 668 which through a connecting rod 670 is connected to arm 672 loosely supported by a stud shaft 674 held by bracket 634. The face end of arm 672 is provided with a nose 676 which projects underneath plate or bar 678 attached to the underside and extending from lug 68 of hub 64 of upper needle bar actuating arm 62. Arm 672 is provided with a tension spring 680 having one end attached thereto; the other end of spring 680 is anchored to collar 682 secured to stationary stud shaft 674 (Fig. 3A), thus providing means of positioning cam follower 662 in the path of travel of lugs 660 on rotating cam 298. A stop screw 684 adjustably mounted in lug 654 and contacting the lower edge of arm 668 provides a stop and rest for the latter when inactive.

Every time a lug 660 contacts cam follower 662, a quick raising and lowering of arm 672 and nose 676 is effected. Since nose 676 is located beneath plate 678, this plate also is raised and lowered. This movement is transmitted to upper needle bar actuating arm 62, and upper needle bar 36 proper, resulting in a quick momentary raising of needle bar 36 through the yieldable connection of hub 64 with hub 76, regardless of the action

of cam lever 90. In this manner each time chuck 520 is turned to or from sewing position, and button receiving and post winding position, it can move without danger of interfering with the movement of needle 96 and needle bar 36.

Post wrapping may be effected by forming a substantially figure eight winding or wrapping passing in between and about the loops of thread attaching a button to the work. This may be accomplished by removing cams 10 434 and 444, and substituting cams 435 and 445, respectively therefor. The movement of table 342 to and from the path of travel of needle 96 is such that during the movement of needle 96 as it travels in the figure eight path under the combined action of cams 435 and 445, needle 96 moves downwardly between the loops of thread, and then upwardly first along one side of the loop and then along the other side of the loops of thread connecting the button to the work or material M. The dwell portion of cam 435 is so designed as to move table 342 slowly towards the path of needle 96 during the post winding operation. This movement guides the winding loops for distribution in side by side relationship along the loops of thread attaching the button to the work. This winding method forms a tight lock post winding 20 automatically locking the winding thread against unwinding or unwrapping because of the way it is disposed between and around the loops of thread connecting the button to the work.

The method employed for sewing a button to a garment 30 or a piece of material with the machine disclosed in the accompanying drawings may be termed a blind stitch method wherein all stitches, with the exception of the first stitched, are made inside or within the thickness of the cloth or material. However, the machine is provided 35 with a stitch adjusting device which enables the machine to make the first stitch also a blind stitch.

As mentioned heretofore, the method of sewing a button to the material with this machine combines two general operations, i. e. a sewing operation, and a stem or post winding operation. The successive steps involved 40 in the sewing operation are illustrated diagrammatically in Figs. 15 to 23, inclusive. The several post winding operations are illustrated diagrammatically in Figs. 24 to 28, inclusive.

In the embodiment of the invention selected for purposes of illustration, needle 96 is shown as having two sharp pointed ends, and an eye located between the ends. If desired needle 96 need only be provided with one sharp point, the other end of the needle being blunt or rounded, as shown in Fig. 33. Needle 97 when formed in this way will, operate satisfactorily because the sewing is in one direction only. That is, the sharp point of the needle moves downwardly through the work, as illustrated in the drawings, and on its upward movement the rounded or blunt end of the needle will pass through a selective button hole only. This type of needle is desirable because it is cheaper to make.

The work or material M to which a button is to be sewed first is folded, as described hereinabove, over gauge plate 332 of work supporting table 342, placing the point at which button B is to be sewed to material M substantially centrally of the free end of gauge plate 332. The latter is then lowered adjacent to the face of table 342, and swung and locked in sewing position, as described heretofore. The operator then takes a piece of thread T of predetermined length, threads needle 96, which at the start of the sewing operations is held by upper needle bar 36 above folded material M on the gauge plate 332 (Fig. 15). The length of thread T preferably is sufficient to sew 3 or 4 buttons. The short end S of the thread T is held or clamped by the thumb or finger of the operator upon the top surface of material M in order to prevent slipping thereof thread during the formation of the first few stitches.

The operator then depresses the knee pedal 576 which

effects the ejection of an aligned button from the bottom of chute 499 and its transfer into jaws 596, 597 of button chuck 520 in the manner described heretofore. At this time jaws 596, 597 are positioned in a substantially vertical position to receive button B (Fig. 15). A suitable tension spring 684, attached to rod 578 of pedal 576 (Figs. 3 and 4), coacts with spring 572 and retracts plunger 522 and causes the disengagement of pins 530 from the holes after button B is pressed into jaws 596 and 597.

The machine is now ready for the sewing operation. The operator trips starting lever 288 which closes switch 290 which causes starting of the machine through the clutch control mechanism illustrated in Fig. 1, and described heretofore. With the button still held in vertical position, upper needle bar 36 descends and pushes needle 96 through the cloth or material M into engagement with lower needle bar 38 (Fig. 16) which then descends and pulls needle 96 completely through the material. Thread puller 318, described hereinabove engages with the loop formed by the thread and pulls the long or loose end thereof through the cloth and deposits it on stationary thread guide drum 482, the short end S of the thread being held by the operator. The action of the thread puller 318 in conjunction with arm 320 and guide drum 482 is fully disclosed in Johnson Patent 2,386,800 and further description thereof is deemed unnecessary. Upper needle bar 36 in the meantime has ascended and is raised momentarily above its normal uppermost position to allow the button chuck 520 to turn free from interference with needle bar 36, and locate button B in a face-up horizontal or sewing position above the selected spot or point on material M to which it is to be sewn.

Work supporting table 342 to which material M is clamped, and which also supports button chuck 520 due to the action of cam 434 has moved towards the front of the machine or to the left, as viewed in (Fig. 9) so that ascending lower needle bar 38 now pushes needle 96 upwardly past the folded edge of material M (Fig. 17) and partly through a hole in the horizontally held button. The protruding end of needle 96 then engages waiting upper needle bar 36 which pulls it upwardly and through hole I of the button (Fig. 22). After needle bar 36 has reached its uppermost position, it descends again a short distance, thereby causing thread T to slack along needle 96 and form loop L above material M. The loop portion to the left of needle 96, as viewed in (Fig. 18), is engaged by pointed finger 686 which in combination with thread guide roller 685 attached to oscillating looper arm 98 is provided for the purpose of pulling the loose end of thread T away from and clear of the path of needle 96 which descends again as soon as the work supporting table carrying the material and the button chuck have moved to a position to permit needle 96 to enter hole II (Fig. 22) of button B (Fig. 19).

A stationary mounted suitably shaped thread guide 687 (Fig. 6) is provided to keep the vertical portion of the loose end of thread T close to lower needle bar 38 in order to assist in forming loop L which can be easily engaged by the pointed finger 686 on looper arm 98. Thread guide 687 is suitably mounted on a frame member of the machine. Needle 96 is pushed downwardly through hole II, and the folded portion of the material by upper needle bar 36, and then engages with lower needle bar 38 which pulls needle 96 completely through buttonhole II, and material M. Thread puller 318 on arm 320 engages the loop formed in thread T beneath work table 342, and pulls the long loose end thereof through buttonhole II and material M (Fig. 20), and disposes the loose portion of thread T about thread guide drum 482. Table 342 and button chuck 520 again move to permit now ascending needle 96 to pass the outer edge of the folded material (Fig. 21) and enter hole III of button B. The protruding end of needle 96 engages with upper needle bar 36 which pulls it through

button hole III. A loop L is formed again and engaged by pointed finger 686 and roller 685 on looper arm 98 and thread T is pulled out of the way of the needle which, after another shift of the table 342 and button 5 chuck 520, descends again and enters hole IV of the button and the folded portion of the material. Lower needle bar 38 again engages needle 96 and pulls it completely through hole IV of button B and the folded portion 10 of the material, thereby resulting in the formation of a blind stitch.

It is to be noted that as shown in (Figs. 17 to 21) inclusive, the thread of all stitches except the first, is contained within the work, that is, between the outer and the inner curved surfaces of the work folded about the free end of gauge plate 332. In this manner, when the work is removed, and flattened out, only a single thread "prick" will appear upon the undersurface of material M, thereby closely simulating a high class "hand" sewn button.

20 Since the combined action of table actuating cams 434 and 444 produce a so-called figure eight motion, the button sewing operations described above are repeated a predetermined number of times wherein needle 96 passes up first from the bottom of button B through hole I, 25 then goes down through hole II and material M, then moves up from the bottom of button B through hole III and goes down through hole IV and the material, after which needle 96 starts up again through hole I. When a button B has been sewn to material M in the manner described by a predetermined number of stitches (Fig. 23), the actual sewing operations are completed. It has been found that three or four complete loops through each 30 pair of button holes results in a good attachment of a button to the work. If desired, the sewing pattern, and 35 number of loops can be changed by changing the shape of cams 434 and 444.

Upper needle bar 36, at the conclusion of the sewing operation, after reaching its uppermost position, is again momentarily raised, thereabove, in order to permit button chuck 520 to turn back to its vertical position, thus locating the bottom side of button B substantially parallel with a plane tangent to the curve of the folded edge of material M on gauge plate 332. Since button B is held by jaws 596 and 597 a predetermined distance away from material M, the stitches connecting button B to material M assumes a substantially horizontal position, as indicated in Figure 24, when button chuck 520 is turned to locate jaws 596 and 597 and button B held therein in a substantially vertical plane. As chuck 520 is turned, 50 button B slides along the loops of thread connecting the button to the work as it moves to the position shown in Figure 24. In the meantime, the work supporting table 342, and button chuck supported therein through action 55 of cam 434, have moved towards the front of the machine again, preventing ascending needle 96 from going through material M. Instead needle 96 passes in front of the folded edge thereof as shown in Fig. 24.

Cam 434 is so designed that table 342 dwells in its 60 forward-most position, and prevents any back and forth motion thereof during the entire post winding operation, except when the last lock stitch is formed. During the entire post winding operation, work table 342 and button chuck 520 are only reciprocated sideways by means of cam 444 to effect a proper winding of stem or post P. The post winding operation starts as needle 96 is pushed upwardly by lower needle bar 38 and since in the meantime table 342 has moved to the left as viewed in Fig. 24, needle 96 passes upwardly alongside the loops of 65 thread connecting the button to the work as shown in Fig. 14.

Needle 96 is then engaged by upper needle bar 36 which pulls it high enough to permit table 342 with material M, button B and chuck 520 to move to the 75 opposite direction such that on the following downward

stroke, needle 96 passes on the opposite side of the loops of thread which are to form stem or post P (Fig. 25). However, before needle 96 descends, loops L, formed by the thread above table 342 and alongside needle 96 in the same manner as described heretofore, is engaged by pointed finger 686 and roller 685 on the oscillating looper arm 98 and moved to a position where the thread is brought in contact with a spring mounted rubber roller 692 (Fig. 26) which is employed for the purpose of giving tension to the loose end of the thread and prevent whipping of the same and at the same time effecting a tighter form of winding around the post P. Needle guide 360 which is located above the work supporting table and acts as a presser foot to hold the work properly positioned thereon for sewing, provides a guide surface which prevents a flexing of the needle 96 out of its proper vertical path of movement. Unless the needle is at all times properly located for transfer from one opposed needle bar to the other, breakage and loss of valuable time in sewing results. For example, when sewing a button to a garment, such as a man's suit or coat, there may be six layers of cloth disposed about gauge plate 332, two of which layers may be buckram, a stiff fabric. When the point of the needle engages this fabric and moves downwardly through the folded work, the needle may tend to flex out of its proper vertical path of movement and therefore is not properly located for engagement with the opposing needle bar to which it is to be transferred. The provision of needle guide 360 obviates this difficulty because the needle moves closely adjacent this guide which is rigidly held against lateral movement and thus proper positioning of the point of the needle is assured.

The main purpose of looper arm 98, is to hold the loose end of thread T out of the path of descending needle 96 (Fig. 26). Thread guide 637 assists in guiding the loose end of thread T as it leaves stationary drum 482.

As mentioned heretofore, the action of looper arm 98 during post winding operations is controlled by looper cam 176 which is brought into engagement with clutch member 102 at the end of the sewing operations when button chuck 520 is turned from a sewing position to post winding position. In continuing the post winding operation, upper needle bar 36 moves the needle downwardly past the left side of the post P (Fig. 26) after which needle 96 is engaged by lower needle bar 38 and pulled to its lowermost position during which time table 342 with material M and button B moves to the left again as viewed in Fig. 26. As lower needle bar 38 starts moving upward again, a loop formed in thread T is engaged by thread puller 318 on rotating arm 320 and the loose end of thread T is pulled down and deposited upon stationary thread guide 482 mentioned heretofore (Fig. 27). Needle 96 during its upward movement now passes the right side of stem P, is then engaged by upper needle bar 36, table 342 and material M move to the right again as viewed in Fig. 27, and needle 96 is pushed downward again past the right side of the post (Fig. 26). These winding operations are repeated a predetermined number of times.

Ten winding or wraps of thread have been found to give satisfactory results, although more or less could be used if desired. This can be accomplished by changing the design of cam 444.

After the completion of the post winding operations thus described, a combined action of cams 434 and 444 upon table 342 takes place, causing the latter to stop momentarily in such a position that upwardly moving needle 96 passes through post P' (Fig. 28), thus locking the end of thread T by stitch F in the "shank" or post. Recess 333 formed in the free end of plate 332 provides an opening for the passage of needle 96 therethrough. After passing through the material, upwardly moving needle 96 is engaged by upper needle bar 36 carried to its uppermost position and the machine stops. Figure 28

illustrates a button B sewed onto the material M with a wrapped post or stem P' after completion of sewing and post winding operation. The operator then cuts off both ends of the thread which protrude from the material and the button sewed thereon can be removed from gauge plate 332 in the manner described heretofore.

If desired, short ends of thread T, which at the beginning of the sewing operations is held by the finger of the operator against the material, may be locked within the post P. For this purpose, a small slotted clamp member 694 (Fig. 4) may be attached to stationary jaw 596 of button chuck 520. Thread T is then threaded through the eye of the needle and the slot in member 694, but the short end is still held by the operator until the first few stitches are made.

As mentioned heretofore and illustrated in Fig. 29, the button sewing machine embodying the invention can be so adjusted that the first stitch also is a blind stitch. For this purpose a flange 696 (Figs. 1, 3A and 9) secured to the top surface of work supporting table 342 carries an upright stud shaft 698 rotatably attached thereto. Stud shaft 698 supports a horizontally adjustable stop screw 700 which may be so adjusted that its end projects over the rear edge of work supporting table 342. Since it is the depth of the first notch 702 on cam 434 (Fig. 7) which controls the relative position of the table and material with respect to needle 96 during the formation of the first stitch, and roller 432 on cam lever 430 is prevented by stop screw 700 from entering into notch 702 to its fullest extent, the edge of material M on table 342 is moved further away from the needle and the latter may pass through the folded edge only of material M instead of behind the folded edge. To secure this condition, the operator swings sew screw 700 when properly adjusted about stud 698 to the left in the direction of the arrow, Fig. 3A, until the shank portion of screw 700 is arrested by a stop pin 704 projecting upwardly from flange 696. The free end of screw 700 then projects beyond the rear edge of table 342 and the latter during its rearward movement by cam 434 is arrested when the free end of screw 700 engages the edge of stop lug 706 (Figs. 1 and 3A). With a different setting of set screw 700, proper, the relative distance between the folded edge position of material M and needle 96 and the desired point on material M through which needle 96 passes, can be adjusted to a very fine degree.

The invention above described may be varied in construction within the scope of the claims, for the particular device, selected to illustrate the invention, is but one of many possible concrete embodiments of the same. It is not, therefore, to be restricted to the precise details of the structure shown and described.

What we claim is:

1. A button sewing machine comprising a work supporting table, a button holding member, a device for projecting a needle and a thread back and forth through holes in said button and said work, means for holding material to which a button is to be sewed on said table, mechanism for moving said table in a substantially four motion path of travel relative to said needle for positioning selected holes in said button in alignment with said needle, means for positioning said button holding member and a button held therein above said work and in a plane substantially parallel to the work during the operation of sewing a button to said work, means for locating said button holding member and said button in a plane substantially at right angles to the plane of said work after said button has been sewed to said work while maintaining said work substantially undisturbed on said table, means operative while said button is held by said button holding member in said plane substantially at right angles to the plane of said work for moving said needle up along one side and down along the opposite side of the loops of thread attaching said button to said work to form a plurality of continuous encircling loops

wrapped about said loops of thread attaching said button to said material, and means for locking said winding thread in said post formed by said loops and windings.

2. A button sewing machine comprising a work supporting table, a button holding member mounted on said table, a device for projecting a needle and a thread back and forth through selected holes in said button and said work, a support plate on said table for holding material to which a button is to be sewed on said table, mechanism for moving said table in a substantially figure eight path of travel relative to said needle and positioning selected holes in said button in alignment with said needle, means for positioning said button holding member and a button held therein in a plane substantially parallel to the work during the operation of sewing a button to said work, means for moving said button holding member and said button into a plane substantially at right angles to the plane of said work after said button has been sewed to said work, and means operative while said button is held by said button holding member in said plane substantially at right angles to the plane of said work for moving said needle up along one side and down along the opposite side of the loops of thread attaching said button to said work to wind a plurality of continuous post forming loops about said loops of thread attaching said button to said material and form a post or shank encircling said loops attaching said button to said work.

3. A button sewing machine comprising a movable work supporting table, a button holding member mounted on said table and movable therewith, means on said table for supporting material to which a button is to be sewed, means for positioning said button holding member with a button therein above said material and in a plane substantially parallel to the plane of said material, means for projecting a needle and a thread back and forth through selected holes in said button and said work to attach said button to said work, means for moving said button holding member into a plane substantially at right angles to the plane of said work, and means for moving said table back and forth in different spaced paths of movement relative to said needle whereby said needle winds a plurality of thread continuous windings about opposite sides of the thread attaching said button to said material.

4. In a sewing machine having a material work support table, a device for projecting a needle and a thread back and forth and completely through selected button holes and work on said table to secure a button thereto, a button support mounted on said work table, means positioning said button support and a button held therein in a plane substantially parallel to said work on said table and spaced therefrom, means for moving said support and said work in a predetermined path in a plane substantially at right angles to the path of movement of said needle to travel said needle and thread back and forth and completely through different selected holes in said button and said work, and completely through selected holes only of said button on each movement of said needle to sew said button to said work.

5. A button sewing machine comprising a work supporting table, a button holding member mounted on said table, said button holder including a pair of opposed jaws, and means holding said jaws in resilient clamping engagement with the periphery of a button, means on said table for supporting material to which a button is to be sewed, means for positioning said button holding jaws of said member with a button held therein above said material and in a plane substantially parallel to the plane of said material with selected holes in said button located above said work and other selected holes located beyond the free edge of said work, means for projecting a needle and a thread back and forth alternately through one of said first-named selected holes in said button and said work on one direction of movement of said needle and through one of said second-

named selected holes only on the next movement of said needle in the opposite direction to attach said button to said work, means for moving said button holding member into a plane substantially at right angles to the plane of said work, and means for moving said table back and forth relative to said needle whereby said needle and thread produce a plurality of thread windings encircling the thread attaching said button to said material.

10 6. A button sewing machine for sewing buttons to material in a manner simulating hand sewing, comprising a work support table, an upper and a lower needle bar located on opposite sides of said table and adapted to alternately project a needle having a thread with a loose end back and forth through selected holes in a button, a thread puller operating in timed relation with said bars for pulling the loose end of said thread through said work and button, means for operating said thread puller, a button holder mounted on said table, mechanism for effecting relative movement between said table and said needle in planes substantially at right angles to each other to dispose said work and button held in said button holder in the path of travel of said needle, mechanism for operating said bars to pass said needle in one direction completely through a selected hole in said button and said work, and in the opposite direction through a selected hole in said button only, whereby said button is attached to said work by a single continuous thread forming a plurality of continuous closed loops, and means operative while said work is on said support table for moving said needle and thread back and forth and round said loops to secure said loops of thread against loosening.

7. A button sewing machine for sewing buttons to material in a manner simulating hand sewing, comprising a work support table, an upper and a lower needle bar located on opposite sides of said support and adapted to alternately project a needle having a thread with a loose end back and forth through selected holes in a button, a thread puller operating in timed relation with said bars for pulling the loose end of said thread through said work and button, a button holder mounted on said table, mechanism for moving said table in timed relation with each movement of said needle to dispose said work and button held in said button holder in the path of travel of said needle, mechanism for operating said bars and thread puller in timed relation with the movement of said table and button holder to pass said needle in one direction completely through a selected hole in said button and said work, and in the opposite direction through a selected hole in said button only, whereby said button is attached to said work by a single continuous thread forming a plurality of continuous closed loops.

8. A button sewing machine comprising a work supporting table adapted to support work having a folded edge to which a button is to be attached, a button support, mechanism for projecting a needle and a thread back and forth through the holes of a button having four button holes, means for locating said button support and a button held therein with two of the button holes located above the folded edge of work held on said table and two button holes located beyond said folded edge of said work, means for moving said table in a closed path of travel relative to the path of movement of said needle in timed relation with each movement of said needle, and means for operating said mechanism simultaneously with the movement of said table to form a plurality of continuous loops of thread passing through said first-named button holes and said folded edge of said work and through the other button holes only of said button whereby to stitch a button to said work.

9. The machine defined in claim 7 including means for moving said button holder and wherein said mech-

anism for operating said upper and lower needle bars includes means for moving said upper needle bar between a lower limit of movement and an upper limit of movement, and means for moving said upper needle bar beyond said upper limit of movement to support said upper needle bar clear of the path of movement of said button holder prior to the operation of said button holder moving means for moving said button holder to and from substantially vertical button supporting position.

10. A button sewing machine for sewing buttons to material in a manner simulating hand sewing, comprising a work support table, an upper and a lower needle bar located on opposite sides of said support and adapted to alternately project a double pointed needle and a thread with a loose end, back and forth through selected holes in a button, a thread puller operating in timed relation with said bars for pulling the loose end of said thread through said work and button, a button holder mounted on said table, a looper mounted above said table, mechanism for moving said table to dispose said work and button held in said button holder in the path of travel of said needle, mechanism for operating said bars and thread puller in timed relation with the movement of said table and button holder to pass said needle in one direction completely through a selected hole in said button and said work, and in the opposite direction through a selected hole in said button only, whereby said button is attached to said work by a single continuous thread forming a plurality of continuous closed loops, means for turning said button holder to move said button along said loops of thread attaching said button to said work and locate said button in a plane substantially at right angles to the plane of said work on said table.

11. The machine defined in claim 10 wherein said mechanism for moving said table includes means for reciprocating said table in a straight line of movement relative to said needle and alternately locating opposite sides of said loops of thread attaching said button to said work in the path of travel of said needle, whereby said needle winds a plurality of windings about said loops of thread attaching said button to said work.

12. The machine defined in claim 11 including means for moving said looper at one rate of speed to engage loop portions of said thread above said work during the stitching of said button to said work, and means for moving said looper at an increased rate of speed to engage said loops when said needle is winding said thread about said loops of thread attaching said button to said work.

13. A button sewing machine for sewing buttons to work in a manner simulating hand sewing, comprising a work support table, an upper and a lower needle bar located on opposite sides of said table and adapted to alternately project a needle, having a sharp end and a blunt end, threaded with a thread with a loose end back and forth through selected holes in a button, a thread puller operating in timed relation with said bars for pulling the loose end of said thread through said work and button, a button holder mounted on said table, mechanism for moving said table and button holder in timed relation with each movement of said needle to dispose said work and button held in said button holder in the path of travel of said needle, mechanism for operating said bars and thread puller in timed relation with the movement of said table and button holder to pass said sharp end of said needle in one direction completely through a selected hole in said button and said work, and the blunt end of said needle in the opposite direction through a different selected hole only in said button, whereby said button is attached to said work by a single continuous thread forming a plurality of continuous closed loops.

14. A button sewing machine comprising means for

supporting an article to which a button is to be sewed for movement into and out of the path of travel of a needle, a device for holding a button above said article, means for projecting a needle and a thread back and forth through the holes in said button to attach said button to said article, means for moving said device while said article remains substantially undisturbed on said supporting means to locate said button in a plane substantially at right angles to the plane of said article, and means operative while said button is held in said last-named plane by said device for locating the sides of the loops of thread connecting said button to said article alternately in the path of movement of said needle, said needle moving up and down on alternate movements along opposite sides of said loops of thread and thereby winding a plurality of continuous post forming loops of thread about said first-named loops and forming a thread post supporting said button away from said article.

15. A button sewing machine comprising a work table, a gauge plate on said table for supporting an article with an edge folded thereover and supported on said gauge plate for movement into and out of the path of travel of a needle, means for supporting a button with half of its holes above said folded edge of said article, means for moving said table in a closed substantially figure eight path of movement, means operative substantially simultaneously with the movement of said table to pass said needle and a thread back and forth through said article and selected holes in said button, means operative in response to the formation of a plurality of loops of thread connecting said button to said article for positioning said button in a plane substantially at right angles to the path of travel of said table, means for controlling the movement of said table relative to said needle to wind a plurality of turns of thread about said loops of thread connecting said button to said article, and means for locking said turns of thread against unwinding.

16. A button sewing machine for sewing buttons to material in a manner simulating hand sewing, comprising a work support table, an upper and a lower needle bar located on opposite sides of said support and adapted to alternately project a needle, having a sharp end and a blunt end, threaded with a thread with a loose end back and forth through selected holes in a button, a thread puller operating in timed relation with said bars for pulling the loose end of said thread through said work and button, a button holder mounted on said table, mechanism including cam means for moving said table and button holder in a closed substantially figure 8 path of travel to dispose said work and button held in said button holder in the path of travel of said needle, mechanism for operating said bars and thread puller in timed relation with the movement of said table and button holder to pass said sharp end of said needle in one direction completely through a selected hole in said button and said work, and the blunt end of said needle in the opposite direction through a different selected hole only in said button, whereby said button is attached to said work by a single continuous thread forming a plurality of continuous closed loops of thread extending unbroken through all of said button holes.

17. A button sewing machine comprising means for supporting an article to which a button is to be sewed for movement into and out of the path of travel of a needle, a device for holding a button above said work, means for projecting a needle and a thread back and forth through the holes in said button to attach said button to said article, means for moving said device to locate said button in a plane substantially at right angles to the plane of said article, mechanism including a cam, operative while said button is held in said last-named plane by said device for locating opposite sides of the loops of thread connecting said button to said article alternately in the path of movement of said needle, said needle thereby winding a plurality of continuous loops

of thread about said first-named loops and forming a thread post supporting said button away from said article, said mechanism also including means for positioning said post of said thread in the path of movement of said needle whereby said needle and thread in passing through said post lock said thread windings against unwinding.

18. A button sewing machine for sewing buttons to work in a manner simulating hand sewing, comprising a work support table, an upper and a lower needle bar located on opposite sides of said support and adapted to alternately project a needle, having a sharp end and a blunt end, threaded with a thread with a loose end back and forth through selected holes in a button, a thread puller operating in timed relation with said bars for pulling the loose end of said thread through said work and button, a button holder mounted on said table, means positioning said button holder in a button receiving position, a button feeding device, means for operating said device when said button holder is located at said button receiving position for feeding a button into said button holder, means for moving said button holder and a button held therein from said receiving position to a button sewing position relative to said work, mechanism for moving said table and button holder to dispose said work and button held in said button holder in the path of travel of said needle, and mechanism for operating said bars and thread puller in timed relation with the movement of said table and button holder to pass said sharp end of said needle in one direction completely through first one selected hole in said button and said work, and the blunt end of said needle in the opposite direction through a selected hole only in said button, whereby said button is attached to said work by a single continuous thread forming a plurality of continuous closed loops.

19. A button sewing machine for sewing buttons to work in a manner simulating hand sewing, comprising a work support table, an upper and a lower needle bar located on opposite sides of said support and adapted to alternately project a needle, having a sharp end and a blunt end, threaded with a thread with a loose end back and forth through selected holes in a button, a thread puller operating in timed relation with said bars for pulling the loose end of said thread through said work and button, a button holder mounted on said table, means positioning said button holder in a button receiving position, a device for feeding a button into said button holder, means for repositioning said button in said holder to align the holes in said button with respect to the path of travel of said needle therethrough, means for moving said button holder and a repositioned button held therein from said receiving position to a button sewing position relative to said work, mechanism for moving said table and button holder to dispose said work and button held in said button holder in the path of travel of said needle, and mechanism for operating said bars and thread puller in timed relation with the movement of said table and button holder to pass said sharp end of said needle in one direction completely through a selected hole in said button and said work, and the blunt end of said needle in the opposite direction through a selected hole only in said button, whereby said button is attached to said work by a single continuous thread forming a plurality of continuous closed loops.

20. A button sewing machine for sewing buttons to work in a manner simulating hand sewing, comprising a work support table, an upper and a lower needle bar located on opposite sides of said support and adapted to alternately project a needle, having a sharp end and a blunt end, threaded with a thread with a loose end back and forth through selected holes in a button, a thread puller operating in timed relation with said bars for pulling the loose end of said thread through said work and button, a button holder mounted on said table, means positioning said button holder in a button receiving posi-

tion, a device for feeding a button into said button holder, button hole engaging elements on said device, means for moving said elements into said holes of a button and displacing said device to transfer said buttons to said button holder, mechanism for oscillating said device to position said button holes for passage of said needle therethrough free from obstruction, means for repositioning said button in said holder to align the holes in said button with respect to the path of travel of said needle therethrough, means for moving said button holder and a repositioned button held therein from said receiving position to a button sewing position relative to said work, mechanism for moving said table and button holder to dispose said work and button held in said button holder in the path of travel of said needle, and mechanism for operating said bars and thread puller in timed relation with the movement of said table and button holder to pass said sharp end of said needle in one direction completely through a selected hole in said button and said work, and the blunt end of said needle in the opposite direction through a selected hole only in said button, whereby said button is attached to said work by a single continuous thread forming a plurality of continuous closed loops.

15 21. A button sewing machine for sewing buttons to work in a manner simulating hand sewing, comprising a work support table, an upper and a lower needle bar located on opposite sides of said support and adapted to alternately project a needle, having a sharp end and a

20 blunt end, threaded with a thread with a loose end back and forth through selected holes in a button, a thread puller operating in timed relation with said bars for pulling the loose end of said thread through said work and button, a button holder mounted on said table, mechanism for moving said table and button holder to dispose

25 said work and button held in said button holder in the path of travel of said needle, and mechanism for operating said bars and thread puller in timed relation with the movement of said table and button holder to pass said

30 sharp end of said needle in one direction completely through a selected hole in said button and said work, and the blunt end of said needle in the opposite direction through a selected hole only in said button, whereby said button is attached to said work by a single continuous thread forming a plurality of continuous closed loops.

35 22. A button sewing machine for sewing buttons to work in a manner simulating hand sewing, comprising a work support table, an upper and a lower needle bar located on opposite sides of said support and adapted to alternately project a needle, having a sharp end and a

40 blunt end, threaded with a thread with a loose end back and forth through selected holes in a button, a thread puller operating in timed relation with said bars for pulling the loose end of said thread through said work and button, a button holder mounted on said table, mechanism for moving said table and button holder to dispose

45 said work and button held in said button holder in the path of travel of said needle, mechanism for operating said bars and thread puller in timed relation with the movement of said table and button holder to pass said

50 sharp end of said needle in one direction completely through a selected hole in said button and said work, and the blunt end of said needle in the opposite direction through a selected hole only in said button, whereby said button is attached to said work by a single continuous thread forming a plurality of continuous closed loops,

55 23. A button sewing machine, a button guide chute, a button holder resiliently supporting a button at the bottom of said chute, a button receiving chuck, support means mounting said chuck for movement therein, means for positioning said chuck in a plane parallel to and spaced from said chute and said button holder for delivery

60 of a button thereto, a button ejector, means for moving said ejector in a direction substantially at right angles to the plane of a button in said button holder to engage a button in said holder and transfer said button from said button holder into said chuck, means on said ejector engaging said button in said chuck for aligning the holes

65 24. A button sewing machine, a button guide chute, a button holder resiliently supporting a button at the bottom of said chute, a button receiving chuck, support means mounting said chuck for movement therein, means for positioning said chuck in a plane parallel to and spaced from said chute and said button holder for delivery

70 of a button thereto, a button ejector, means for moving said ejector in a direction substantially at right angles to the plane of a button in said button holder to engage a button in said holder and transfer said button from said button holder into said chuck, means on said ejector engaging said button in said chuck for aligning the holes

75 25. A button sewing machine, a button guide chute, a button holder resiliently supporting a button at the bottom of said chute, a button receiving chuck, support means mounting said chuck for movement therein, means for positioning said chuck in a plane parallel to and spaced from said chute and said button holder for delivery

80 of a button thereto, a button ejector, means for moving said ejector in a direction substantially at right angles to the plane of a button in said button holder to engage a button in said holder and transfer said button from said button holder into said chuck, means on said ejector engaging said button in said chuck for aligning the holes

85 26. A button sewing machine, a button guide chute, a button holder resiliently supporting a button at the bottom of said chute, a button receiving chuck, support means mounting said chuck for movement therein, means for positioning said chuck in a plane parallel to and spaced from said chute and said button holder for delivery

90 of a button thereto, a button ejector, means for moving said ejector in a direction substantially at right angles to the plane of a button in said button holder to engage a button in said holder and transfer said button from said button holder into said chuck, means on said ejector engaging said button in said chuck for aligning the holes

in said button for subsequent passage of a needle there-through, and means for turning said chuck in said support means to move said button in said chuck from a receiving position to a sewing position above the work to which said button is to be attached.

24. In a button sewing machine, a button guide chute, a button holder supporting a button in said chute, a button receiving chuck, support means mounting said chuck for movement therein, means positioning said chuck in one plane for receiving a button therein, a button ejector, means for moving said ejector to engage a button in said holder and transfer said button to said chuck, and means for moving said chuck and a button held therein from said first-named plane substantially at right angles thereto to a button sewing plane for passage of a needle there-through.

25. In a button sewing machine, a button guide chute, a button holder in said chute for holding a button in a substantially vertical plane, a button receiving chuck, a support mounting said chuck for movement therein, means positioning said chuck in a button receiving position in a substantially vertical plane, a button ejector, means for moving said ejector to deliver a button from said holder to said chuck, and means for moving said chuck and button from said receiving position in said substantially vertical plane to button sewing position in a substantially horizontal plane relative to material to which said button is to be sewed.

26. In a button sewing machine, a button guide chute, a button holder in said chute, a button receiving chuck, a support mounting said chuck for movement therein, means positioning said chuck in a button receiving position, a button ejector, means for moving said ejector to deliver a button from said holder to said chuck, means for aligning the holes in said button in said chuck for passage of a needle therethrough, and means for moving said chuck and button from said receiving position in a substantially vertical plane to button sewing position in a substantially horizontal plane relative to material to which said button is to be sewed.

27. In a button sewing machine, a button chute, a button holder in said chute, a work supporting table, a button chuck mounted on said table, means for positioning said chuck in button receiving position in a substantially vertical plane parallel to and spaced from said button holder, an ejector for ejecting a button from said holder and delivering said button to said chuck, and means for moving said chuck and a button held therein through an angular path of movement from receiving position to sewing position in a substantially horizontal plane above the work supported on said table.

28. The machine defined in claim 27 including means for projecting a threaded needle back and forth on alternate movements through different holes in said button, and mechanism for effecting relative movement between said needle and said table and button chuck to position said different selected button holes in said button for passage of said needle and thread therethrough.

29. The machine defined in claim 27 including opposed needle bars, and means for moving said bars to project a double pointed needle back and forth through work on said table and holes in said button, and mechanism for effecting relative translatory movement between said table, button chuck and work supported by said table and said needle in planes substantially at right angles one to the other, to project said needle through a selected hole in said button and said work, and a different selected hole in said button only on each movement of said needle to attach said button to said work.

30. The machine defined in claim 27 including opposed needle bars, and means for moving said bars to project a double pointed needle back and forth through work on said table and holes in said button, mechanism for effecting relative translatory movement between said table, button chuck and work supported by said table and

said needle in planes substantially at right angles one to the other, to project said needle through selected holes in said button and said work, and selected holes in said button only to attach said button to said work, means operative in response to the completion of a plurality of loops of thread attaching said button to said work for turning said button chuck from said sewing position to a position substantially at right angles thereto, whereby said button slides along said loops of thread and is positioned in a plane substantially at right angles to the plane of said sewing position, said last-named mechanism including means for restricting the movement of said chuck and table to a substantially straight line reciprocatory path of motion to locate first one side and then the other side of said loops of thread in the path of travel of said needle, whereby a plurality of windings of thread are wrapped about said loops to form a self-supporting stem, and means for locking said windings against unwrapping.

31. A button sewing machine comprising a material support table, an upper and a lower needle bar located on opposite sides of said table, said bars being adapted to project a double pointed needle with a thread having a fixed and a loose end back and forth through holes in a button for sewing the same to said work, a chuck for positioning said button above said work, means for moving said chuck and a limited portion of said work in a path substantially at right angles to the movement of said needle to cause said thread to be moved in continuous closed paths whereby to sew said button by closed continuous loops of thread to said work, means operative in response to the completion of sewing said button to said work and while said work remains substantially undisturbed on said table for positioning said chuck and button in a plane substantially at right angles to the plane of said support and means for continuing the operation of said needle bars to move said needle first in one direction along one side, and then in the opposite direction along the opposite side of the loops of thread connecting said button to said work for winding a plurality of post forming wraps of thread about said thread connecting said button to said work.

32. A sewing machine for use in sewing buttons to the folded edge of a selected material in a manner simulating hand sewing, comprising a pair of opposed needle bars constructed and arranged to project a needle having a thread with a loose end back and forth through a button and the folded edge of the material to which said button is to be attached, means for supporting said button with half of its holes located above said folded edge of said material and the other half of its holes positioned beyond said folded edge of said material, means for operating said bars to form a plurality of stitches wherein on one direction of movement of said needle, said thread is passed through a selected hole in said button and said folded edge of said material, and on the next movement of said needle in the opposite direction, said thread is passed through a different selected hole only to form a plurality of continuous loops of thread attaching said button to said material, means operative cyclically for pulling the loose end of said thread through said button and said material, and means for forming a plurality of continuous thread windings about said loops of thread, and means for securing said thread windings against loosening.

33. The invention defined in claim 32 wherein said button supporting means comprises a pair of opposed button holding jaws, a movable support for said jaws, means for locating said jaws in a button receiving position, means for delivering a button between said jaws, and means for moving said support to position a button held between said jaws in a plane substantially at right angles to said button receiving position and adjacent said folded edge of said material to which said button is to be attached.

34. In a button sewing machine of the type described, a work support table adapted to support an article having a folded edge to which edge a button is to be attached,

means mounting said table for movement in a substantially four motion path of travel in a plane substantially at right angles to the path of movement of a needle, a movably mounted work supporting gauge plate mounted on said table, means for holding said gauge plate in fixed operative position on said table, and supports mounting said plate for movement into and out of said fixed position for placement and removal of work on and from said table.

35. The invention defined in claim 34 wherein said gauge plate is provided with a recess at its free end, said recess providing an opening for the travel of a needle therethrough during the attachment of a button to material positioned on said plate.

36. The invention defined in claim 34 including a support mounted on said table, a button chuck movably mounted in said support, means for mounting said button chuck for movement to a button receiving position, and to a post winding position, said position being substantially parallel to the path of movement of said needle, and means for moving said chuck to a substantially horizontal button sewing position above the folded edge of the material to which a button is to be attached.

37. The invention defined in claim 36 including coacting cams for moving said table and said button chuck carried thereby in a predetermined path of travel relative to the path of movement of said needle, and means for moving said upper needle bar clear of the path of movement of said button chuck as said button chuck moves from its vertical position to its button sewing position, and from its button sewing position to its post winding position.

38. The invention defined in claim 34 comprising coacting cams for traveling said table in said four motion path of movement relative to said needle, and adjusting means for restricting the movement of said table to and from the path of movement of said needle to position the folded edge of said article to which a button is to be attached for the passage of said needle entirely within the inner and outer faces of said folded edge of said material whereby a button is blind sewed to said material.

39. The invention defined in claim 36 including a cam for moving said table to and from the path of travel of said needle, and a cam for moving said table in a plane substantially at right angles to the plane of movement of said needle, a shaft supporting said cams for coacting operation for moving said table and said button chuck carried thereby in a substantially figure 8 path of movement, and means for driving said shaft, said last-named cam having means for positioning the continuous loops of thread connecting a button to said work relative to said needle such that said needle travels the thread in a substantially figure 8 path of movement in and about said loops of thread in forming a post, and locks said thread against unwinding.

40. The invention defined in claim 2, including a slotted thread clamp member mounted on said button holding member, said slot in said clamp member providing means for holding an end of said thread against displacement during the formation of the first loops of thread connecting said button to said work.

41. A button sewing machine comprising mechanism for supporting the folded edge of work to which a button is to be sewed in the path of movement of a threaded needle, a support for holding a button above said folded edge of said work for attachment thereto, a device for aligning selected different button holes of said button in said support for passage of said needle in different paths of movement therethrough, and means for moving said needle back and forth through said different selected button holes and said work to sew said button thereto, said device including an ejecting rod having a button engaging head, fixed means mounting said rod in a plane substantially at right angles to the path of movement of said needle, a source of supply of buttons, a button feed chute,

means for moving said rod in one direction to eject a button from said chute and locate said button in said button support, means for imparting rotary movement to said rod to locate the holes in said button in aligned relationship with said needle, and means for moving said rod in the opposite direction clear of said button and out of the path of movement of said needle.

42. A button sewing machine comprising mechanism for supporting the folded edge of work to which a button is to be sewed in the path of movement of a threaded needle, a support for holding a button above said folded edge of said work for attachment thereto, a device for aligning selected different button holes of said button in said support for passage of said needle in different paths of movement therethrough, and means for moving said needle back and forth through said different selected button holes and said work to sew said button thereto, including mechanism for forming a plurality of continuous wraps of thread about the loops of thread connecting said button to said work, said mechanism including means for directing said needle back and forth through said loops in a substantially figure 8 path of movement.

43. In a button sewing machine, a button guide chute, a movable work supporting table, a button holder mounted on said table for movement therewith, said button holder including a movably mounted button chuck, means for moving said chuck into button receiving position adjacent said button guide chute, a button ejector for removing a button from said button guide chute and delivering said button into said chuck, means for aligning the holes of said button for passage of a needle therethrough, and means for moving said chuck through an arc of substantially 90° from said receiving position to a sewing position relative to the work on said table for attachment of said button to said work.

44. A sewing machine for use in sewing buttons to the folded edge of a selected material in a manner simulating hand sewing, comprising a pair of opposed needle bars constructed and arranged to project a needle having a thread with a loose end back and forth through a button and the folded edge of the material to which said button is to be attached, means for supporting said button with half of its holes located above said folded edge of said material and the other half of its holes positioned beyond said folded edge of said material, means for operating said bars to form a plurality of stitches wherein on one direction of movement of said needle, said thread is passed through a selected hole in said button and said folded edge of said material, and on the next movement of said needle in the opposite direction, said thread is passed through a different selected hole only, means operative cyclically for pulling the loose end of said thread through said button and said material, means for securing said plurality of stitches against unwinding, said means for supporting a button comprises a button chuck, a movable mount for said chuck, means for moving said mount to position said chuck with a button held therein in a plane above and substantially parallel with said folded edge of said material, means operative in response to the completion of a plurality of loops of thread connecting said button to said folded edge of said material for moving said mount to position said button held in said chuck in a plane substantially at right angles to the plane of said material, means for effecting relative sidewise reciprocatory movement between said loops of thread connecting said button to said material and said needle to wind a plurality of wrappings about said loops of thread and form a post, and means for securing said thread against unloosening.

45. A button sewing machine comprising mechanism for supporting the folded edge of work to which a button is to be sewed in the path of movement of a threaded needle, a support for holding a button with selected holes of said button above said folded edge of said work and with other selected holes located beyond said folded edge

of said work for attachment thereto, a device for moving said support to align selected different button holes of said button held in said support for passage of said needle in different selected paths of movement on each movement of said needle and a continuous thread there-through, means for moving said needle in one direction of movement through one of said selected first-named button holes and said work and in the opposite direction of movement through one of said other selected second-named holes only of said button to sew said button there-to by a plurality of loops of said continuous thread passing through said work and said button holes, and means operative while said work is supported by said mechanism

5

10

for moving said needle back and forth around said loops of thread to secure them against loosening.
